UNITED STATES PATENT OFFICE.

MORTIMER HYMAN, OF NEW YORK, N. Y.

DESIGN FOR A TOOTH-BRUSH HANDLE.

SPECIFICATION forming part of Design No. 25,170, dated February 18, 1896.

Application filed December 4, 1895. Serial No. 571,061. Term of patent 7 years.

To all whom it may concern:

Be it known that I, MORTIMER HYMAN, of New York city, New York, have invented and produced a new and original Design for Tooth-
5 Brush Handles, of which the following is a specification, reference being had to the accompanying drawings, in which—

Figure 1 is a perspective view of a tooth-brush provided with my newly-designed handle. Fig. 2 is an edge view thereof; Fig. 3, a cross-section on line 3 3, Fig. 2; and Fig. 4, a cross-section on line 4 4, Fig. 2.

The leading feature of my design consists of a tooth-brush handle which has one rounded 15 blunt edge, one sharp edge and sides that converge from the blunt toward the sharp edge.

a is the head, *a'* the neck, and *a²* the stem, of a tooth-brush handle. The stem *a²* has one rounded blunt edge *a³*, one sharp edge *a⁴*, and 20 sides that converge from the blunt toward the sharp edge, Figs. 3 and 4. Moreover the stem *a²* tapers from end to end, being thickest at its junction with the neck and thinnest at its rear end. 25

What I claim is—

The design for a tooth-brush handle, substantially as herein shown and described.

MORTIMER HYMAN.
